UNITED STATES PATENT OFFICE.

SAMUEL J. BRANSON AND EDWARD C. STRATHMANN, OF INDIANAPOLIS, INDIANA,
ASSIGNORS TO THE CONCRETE FORMS COMPANY, OF INDIANAPOLIS, INDIANA, A
CORPORATION OF INDIANA.

FALSEWORK FOR CONCRETE FLOORS.

1,314,567.

Specification of Letters Patent.

Patented Sept. 2, 1919.

Application filed October 13, 1916. Serial No. 125,352.

To all whom it may concern:

Be it known that we, SAMUEL J. BRANSON and EDWARD C. STRATHMANN, citizens of the United States, residing at Indianapolis, in the county of Marion and State of Indiana, have invented a new and useful Falsework for Concrete Floors, of which the following is a specification.

It is the object of our invention to provide, for the construction of concrete floor slabs, a falsework structure which shall be inexpensive in construction as well as in installation and removal, can be built on the ground of ordinary lumber, can be put up and removed with a minimum of labor, can be re-used as often as desired, is automatically given the proper spacing when set up, produces the most economical distribution of concrete, and eliminates the use of expensive fillers of clay tile, steel tile, or gypsum blocks, which are used between joists in other methods of construction.

This application has certain subject-matter in common with our co-pending application Ser. No. 115,594, filed August 18, 1916, of which prior application this application is in part a continuation. The claims covering the subject-matter common to the two applications are presented in this application.

The accompanying drawings illustrate our invention. Figure 1 is an enlarged horizontal partial section through a false work embodying our invention, showing the attachment for the forms at the ends of the joists; Fig. 2 is a section on the line 2—2 of Fig. 1, showing in dotted lines the end piece before it is lowered in place; Fig. 3 is a sectional view through a bench on which the adjacent L-shaped members for adjacent joists are fastened together to form a constructional unit; Fig. 4 is a sectional view showing the construction of sheet metal instead of wood; Fig. 5 is a view showing the L-shaped members with inclined uprights; Fig. 6 is a view showing a form of our falsework which is assembled and held together in proper opened relation without nails so that it can be most easily put up and taken down; and Fig. 7 is a view similar to Fig. 6, but is taken from another angle, so that it shows in a single view the forms for the girders, the joists, and the floor slabs, together with the end construc-

tion for forming the girder side faces between joints.

In the construction of concrete floors in buildings, there is usually a flat floor slab 10 which is crossed on its under side by parallel joists 11 extending in one direction, which joists rest on a smaller number of parallel beams or girders 12 or masonry walls extending in a direction transverse to the joists. The girders are heavier than the joists, and are usually constructed of steel I-beams which may or may not be embedded in concrete or of concrete with the usual embedded reinforcing steel rods. The joists are usually of concrete, integral with the floor slab, and are also conveniently provided with suitable reinforcing rods 14. Frequently the girders are provided with an enlarged upper portion so as to produce a T-shaped cross section.

Heretofore, in constructing floors of this character, parallel rows of tile have ordinarily been used to fill the downwardly opening grooves between adjacent joists, such tile sometimes being left in place and sometimes being removed. These tiles have in most cases been of terra-cotta, though in recent constructions "metal tile" and plaster blocks have been used to some extent. In any of these cases, the tile or blocks have ordinarily been supported on a complete false floor, and something in addition to such tile or blocks has been used to furnish forms for the under faces of the joists. Moreover, skilled labor has ordinarily been required for placing the tiles or blocks which constitute the forms for the bottom of the floor slab and the sides of the joists, for the tiles must be placed in parallel rows with considerable accuracy.

We do away with the necessity for this false floor, and for the necessity of the great care in placing the forms on such false floor. In addition, we construct our forms so that they can readily be put in place, and readily and easily be removed after the concrete has been poured in the forms and hardened, without destroying the forms, so that they can be used again.

To this end, we provide form members 20 which extend longitudinally of the proposed joists and are L-shaped in cross section, as clear from Fig. 5, the stems or uprights of these L-shaped members being

- formed of wooden planks set edgewise and being either vertical as shown in Figs. 6 and 7 or slightly inclined as shown in Fig. 5. The use of inclined upright portions in these 5 L-shaped members to some extent facilitates removal of the forms after the completion of the floor, and also provides for additional concrete at the top of the joists, where the concrete is sometimes desired to take the 10 compression stresses, but the vertical upright portions give the most economical distribution of concrete. These L-shaped members are alternately oppositely placed, in spaced pairs with the free edges of the horizontal portions 21 of each pair abutting to form a soffit, but not being connected. The form for the bottom and sides of a joist is produced by this mating of such two members, and in addition the vertical portions 15 of such members 20 take the place of the temporary joists ordinarily used for supporting the false floor on which the tile or blocks and the deposited concrete rest. The proper distance between adjacent joists 20 is obtained by spacing apart adjacent pairs of members 20. For this purpose, the outer faces of the uprights of the L-shaped members are provided with vertical cleats 22 nailed thereto, and corresponding cleats on 25 adjacent L-shaped members of adjacent pairs are connected by edgewise spacing members 23, conveniently fastened to the cleats 22 by nails 24 which are not driven completely home, so that they may easily be 30 removed when dismantling the forms. The two adjacent L-shaped members 22 of two adjacent pairs and their connecting spacing members 23 form a unit of construction, which without requiring particular skill 35 can be placed in position and abutted against similar units to produce parallelism.
- To form these constructional units, a bench 25 (Fig. 3) is provided, such bench having spacing blocks 26, 27, and 28 between which are spaces into which the L-shaped members 20 may be placed, with the cleats 22 already on them. These spacing blocks 26, 27, and 28 properly space the lower parts of the members 20, while a 40 loose spacing strip 29 spaces their upper parts. With the L-shaped members thus properly spaced, the spacing members 23 are nailed to the cleats 22, to produce the constructional unit.
- 45 The constructional units composed of two oppositely placed L-shaped members 20 and their connecting spacing members 23 furnish supports for top pieces 30, which are of proper width to fit between the uprights of such L-shaped members, as clear from Figs. 6 and 7, and conveniently rest on either the cleats 22 or the connecting spacing members 23. Preferably the top pieces are not fastened to the constructional units, as 50 thereby dismantling is facilitated; though

with the inclined upright portions shown in Fig. 5 the forms may be removed without collapsing, so that the top pieces may be permanently fastened to such constructional units. The parts on which such top pieces 70 rest are properly spaced from the upper edges of the uprights of the L-shaped members so that the upper faces of such top pieces 80 are flush with the upper edges of such uprights. The top piece 30 is shown as composed of a number of planks, connected by cleats 31 to which they are nailed. The edges of such top pieces are beveled downwardly, so that when the forms are dismantled the lower edges of such top pieces 80 do not interfere with swinging the L-shaped members 20 away from the joists 11 to separate the forms from the concrete. This swinging in of the L-shaped members 20 can easily be accomplished by first removing the 85 nails 24, thereby permitting the spacing connecting members 23 to drop out. The constructional units with their associated top pieces comprise mating forms which are readily put together.

90 The constructional units composed of the L-shaped members 20 with their connecting spacing members 23 rest on any suitable number of spaced transversely extending members, for each row of units there are a 95 central edgewise supporting member 35 supported by a suitable framework 36 and two end edgewise supporting members 37 supported by the framework structures 38 which carry the forms 39 for the joists 12. The 100 space between any two adjacent supporting members 35 and 37 is materially greater than the height of the vertical portions of the L-shaped members 20, so that there is made effective the beam action of such members, 105 more particularly of the vertical portions of such members, which by reason of being edgewise are very rigid against vertical bending. This rigidity of the vertical portions is transmitted to the horizontal portions 21 by reason of the rigid connection between such vertical and horizontal portions. As a result, the vertical portions of the L-shaped members act both as forms for the concrete joists and as supporting beams 110 for the horizontal portions 21 and for the concrete which is placed thereon to form the concrete joists. The L-shaped members 20 are sufficiently strong against vertical bending that they are self-supporting between 115 the spaced supports 35 and 37, and are also sufficiently strong to carry the load, not only of their own weight and of the top pieces 30, but of the entire floor slab 10 and joists 11 with their embedded rods 14.

120 The ends 40 of the upright portions of the L-shaped members 20 and the ends 41 of the top pieces 30 are beveled as shown in Figs. 1 and 2, so that such portions are longer on the faces away from the concrete than on 125

130

those toward the concrete; and these beveled ends coöperate with flanges 42 and 43 at the edges of and on the face away from the concrete of end members 44, as shown in 5 Figs. 1 and 2, constituting the forms for the vertical faces of the girders between joists. These end members are slid vertically in place, from the dotted line position to the full line position shown in Fig. 2, after the 10 remainder of the false-work has been erected. In order to lock these end members 44 in place, their faces away from the concrete may be provided with guide plates 45 which coöperate with flanged guide plates 46 carried by the cleats 22 and 31, the locking flanges of the guide plates 46 projecting toward the concrete so as to permit such plates and their associated parts to be moved away from the concrete for dismantling the 15 20 remainder of the forms while the end members 44 are still in place.

In operation, the framework structures 36 and 38 are set up, with the girder forms 39 and the supporting members 35 and 37 in 25 place thereon. Then the constructional units, each composed of two spaced oppositely placed L-shaped members with their connecting spacing members 23, are successively placed on the supporting members 35 and 30 37, transversely thereof, adjacent construction units abutting by the engagement of the free edges of the horizontal flanges 21 of such L-shaped members. Each pair of abutting horizontal flanges 21 coöperate to 35 form a soffit. Thus the forms for the joists are provided. Then the top pieces 30 are put in place, to provide the form for the under face of the floor slab, and finally the end pieces 44 are dropped in place. This 40 completes the forms. The reinforcement is now put in place. Then the concrete is poured. When the concrete has hardened, the forms are dismantled. For this purpose, the framework 36 and 38 is taken down; the 45 nails 24 are pulled out to permit the dropping of the connecting spacing members 23; then the L-shaped members 20, which are now disconnected from other L-shaped members by reason of the removal of the connecting spacing members 23, are swung outward, using their upper edges as centers, and lowered; this frees the top pieces 30, which are now dropped; and then the end pieces 44 are swung outward and dropped. 50 55 This completes the freeing of the forms for the finished floor structure.

The forms thus far described have been wooden forms, which are exceedingly convenient in manufacture and use, as they can 60 be made on the ground from ordinary lumber. However, the concrete-engaging parts may also be formed of sheet metal, as illustrated in Fig. 4. Here the L-shaped members 20' have horizontal portions 21', each of which mates 65 with a similar horizontal portion of an

adjacent L-shaped member to form thereby a joist form, the free edges of the horizontal portions 21' conveniently being provided with down-turned flanges 50 which project into notches 51 in the supporting members 35 and 37. The upper edges of the upright portions of the L-shaped members 20' are turned outwardly and then displaced downwardly to form rabbets 52, and in such rabbets of adjacent L-shaped members 20' of 75 adjacent pairs rest flat sheet metal top pieces 30'. The L-shaped members at the outer edges of the rabbets 52 are provided with downwardly extending flanges 53, which project into notches 54 in uprights 55 nailed 80 to and projecting upward from the supporting members 35 and 37, so as to provide spacing supports for the L-shaped members 20. This sheet metal structure is assembled by placing the L-shaped members 20' on the 85 supports 35 and 37 so that the flanges 50 and 53 project into the notches 51 and 54, and then laying the top pieces 30' in place with their edges engaging the pockets 52. It is dismantled by first removing the supporting members 35 and 37, and then swinging the L-shaped members 20' around their upper edges to disengage them from the deposited concrete, and finally moving the top pieces 30' downward from the under 90 faces of the floor slab.

Instead of providing the constructional units each composed of two of the L-shaped members 20 connected by spacing members 23 nailed to the cleats 22, we may provide 100 for properly spacing the L-shaped members without such nailing, thus facilitating assembling and dismantling. Such an arrangement is illustrated in Fig. 6. The L-shaped members 20 as in the other instances 105 rest on spaced supports 35 and 37, and on the upper edges of these spaced supports are nailed cleats 60 properly spaced apart so that the spaces between them are of just sufficient width to receive the lower edges of 110 two mating L-shaped members with the horizontal portions 21 thereof abutting, the ends of the cleats 60 preferably being upwardly beveled so that the bearing between them and the L-shaped members is only at 115 the bottoms of the cleats. Beside each cleat 60 there are also fastened to the spaced supports 35 and 37 an upright 61, corresponding to the upright 55 in the sheet metal construction shown in Fig. 4, the upper edges 120 of which uprights may serve as supports for the top pieces 30, which are of the same construction as already described. If any additional supports are needed for these top pieces, they may be provided by loose cross 125 boards 62 resting on cleats 63, of proper height, which cleats are nailed to the outer faces of the L-shaped members 20 at suitable points. The uprights 61 are preferably narrower at the bottom than the clear space 130

between adjacent L-shaped members 20 for adjacent joists, so as to provide clearance to facilitate assembling and dismantling, and their upper corners 64 are notched and provided with upwardly extending metal tongues 65 overlapping such notches to provide pockets for receiving horizontal metal strips 66 carried by cleats 67 on the outer vertical faces of the L-shaped members 20. 5 The engagement of the strips 66 in the pockets formed by the notches 64 and tongues 65 positions the upper edges of the L-shaped members 20, so that this in connection with the cleats 60 firmly positions such 10 members throughout. By this construction the spaced supports 35 and 37 and their supporting framework are erected, and then the L-shaped members 20 are dropped in place with their lower edges between the 15 cleats 60 and with the straps 66 in the pockets formed by the notches 64 and tongues 65. Then the cross boards 62 are put in place. Then the top pieces 30 are laid in place on the upper edges of the uprights 61 and on the cross boards 62, and the end 20 members 44 (not shown in Fig. 6, but of the same construction as already described,) are dropped in place, and the structure is 25 complete, ready for the pouring of the concrete. When the concrete is hardened, the spaced supports 36 and 37 together with the cleats 60 and uprights 61 are removed, with or without removing their supporting framework, which removal by reason of the character 30 of the engagement is obtained without interfering with the other parts of the structures. Then the L-shaped members 20 are swung outward and lowered in the manner already described, which can be done 35 without requiring the removal of any nails. Then the top pieces 30 are lowered, and finally the end pieces are swung outward and dropped.

We claim as our invention:

1. A falsework for concrete floor slab constructions of the joist type, comprising a plurality of spaced supports, a plurality of combined beam and form members resting on said supports and spanning the 50 spaces between them, each of said members comprising a longitudinal upright portion and a longitudinal horizontal portion having support upon said upright portion and projecting laterally from the lower edge 55 thereof, both portions spanning spaces between said supports to constitute forms for the joists, and said members being alternately oppositely placed and mating in pairs at the projecting edges of said horizontal 60 portions, the pairs of such members being spaced apart, a plurality of top pieces 66 operating with the upper edges of and having support upon the upright portions of adjacent members of adjacent pairs and closing 65 the space between such pairs to constitute

forms for the under surface of the slab, the spaced supports being spaced apart by distances materially greater than the height of said upright portions so that they are sufficiently far apart so that said members act as 70 beams as well as forms, and said members being sufficiently rigid as beams to carry the load of the superposed concrete, and spacers connecting adjacent members of adjacent pairs to form constructional units, said connecting 75 spacers and the members with which they are associated being readily detachable from each other.

2. A falsework for concrete floor slab constructions of the joist type, comprising supports, a plurality of form members resting on said supports, said members being placed in spaced pairs, a plurality of top pieces co-operating with the upper edges of adjacent members of adjacent pairs and closing the 80 space between such pairs to constitute forms for the under surface of the slab, and end pieces each detachably co-operating with the ends of a top piece and of the two form members associated with such top pieces to 85 close the ends of the spaces therebetween, said end pieces interlocking with the top pieces and the form members to hold the end pieces in place while permitting the removal of the top pieces and the form members 90 before the end pieces after the pouring of the concrete.

3. A falsework for concrete construction, comprising a plurality of spaced supports, a plurality of members resting on and extending transversely to said supports, said members being L-shaped in cross section and alternately oppositely placed and mating in pairs at the projecting edges of the horizontal portions of said L-shaped members, the 100 pairs of L-shaped members being spaced apart, a plurality of top pieces co-operating with the upper edges of the uprights of the adjacent L-shaped members of adjacent pairs and closing the space between such pairs, the 105 L-shaped members being sufficiently rigid so that they are self-supporting between said supports and will carry the superposed concrete, and parts rigid with spaced supports for interlocking with and properly positioning and spacing the pairs of L-shaped members.

4. A falsework for concrete floor slab constructions of the joist type, comprising a plurality of spaced supports, a plurality of 110 combined beam and form members resting on said supports and spanning the spaces between them, each of said members comprising a longitudinal upright portion and a longitudinal horizontal portion having support 115 upon said upright portion and projecting laterally from the lower edge thereof, both portions spanning spaces between said supports to constitute forms for the joists, and said members being alternately oppositely 120 positioned.

placed and mating in pairs at the projecting edges of said horizontal portions, the pairs of such members being spaced apart, a plurality of top pieces cooperating with the upper edges of and having support upon the upright portions of adjacent members of adjacent pairs and closing the space between such pairs to constitute forms for the under surface of the slab, the spaced supports being spaced apart by distances materially greater than the height of said upright portions so that they are sufficiently far apart so that said members act as beams as well as forms, and said members being sufficiently rigid as beams to carry the load of the superposed concrete, and spacers releasably attached to adjacent members of adjacent pairs for properly spacing such pairs apart.

5. A falsework for concrete construction, comprising a plurality of spaced supports, a plurality of members resting on and extending transversely to said supports, said members being L-shaped in cross section and alternately oppositely placed and mating in pairs at the projecting edges of the horizontal portions of said L-shaped members, the pairs of L-shaped members being spaced apart, a plurality of top pieces coöoperating with the upper edges of the uprights of the adjacent L-shaped members of adjacent pairs and closing the space between such pairs, the L-shaped members being sufficiently rigid so that they are self-supporting between said supports and will carry the superposed concrete, and parts rigid with said spaced supports for interlocking with and properly positioning and spacing the pairs of L-shaped members, said interlocking permitting said spaced supports and spacing parts to be withdrawn from said L-shaped members to release the latter for removal from against the concrete.

6. A falsework for concrete construction, comprising a plurality of spaced supports, a plurality of members resting on and extending transversely to said supports, said members being L-shaped in cross section and alternately oppositely placed and mating in pairs at the projecting edges of the horizontal portions of said L-shaped members, the pairs of L-shaped members being spaced apart, a plurality of top pieces coöoperating with the upper edges of the uprights of the adjacent L-shaped members of adjacent pairs and closing the space between such pairs

the L-shaped members being sufficiently rigid so that they are self-supporting between said supports and will carry the superposed concrete, and parts for interlocking with and properly positioning and spacing the pairs of L-shaped members, said top pieces removably resting on said spacing parts. 60

7. A falsework for concrete construction, comprising a plurality of spaced supports, a plurality of members resting on and extending transversely to said supports, said members being L-shaped in cross section and alternately oppositely placed and mating in pairs at the projecting edges of the horizontal portions of said L-shaped members, the pairs of L-shaped members being spaced apart, a plurality of top pieces coöperating with the upper edges of the uprights of the adjacent L-shaped members of adjacent pairs and closing the space between such pairs, the L-shaped members being sufficiently rigid so that they are self-supporting between said supports and will carry the superposed concrete, and parts rigid with spaced supports and properly positioning and spacing the pairs of L-shaped members.

8. In combination in a concrete falsework, an inverted channel-shaped member the sides of which are collapsible toward each other, and an end member closing the end of said channel and abutting against the ends of said channel-shaped member, the junction between said end member and said channel-shaped member providing draft whereby when the channel-shaped member is covered with concrete its sides may be collapsed and the member withdrawn from the concrete while the end piece remains in place.

9. In combination in a concrete falsework, 95
an inverted channel-shaped member, and an
end member closing the end of said channel
and abutting against the ends of said chan-
nel-shaped member, the junction between
said end member and said channel-shaped 100
member providing draft permitting one of
such parts to be readily withdrawn from the
concrete while the other remains in place.

In witness whereof, we have hereunto set our hands at Indianapolis, Indiana, this 11th day of October, A. D. one thousand nine hundred and sixteen. 105

SAMUEL J. BRANSON.
EDWARD C. STRATHMANN
